UNITED STATES PATENT OFFICE.

ROBERT W. IVEY, OF NEW LONDON, NORTH CAROLINA.

PINLESS CLOTHES-LINE.

SPECIFICATION forming part of Letters Patent No. 769,222, dated September 6, 1904.

Application filed February 2, 1904. Serial No. 191,690. (No model.)

To all whom it may concern:

Be it known that I, ROBERT W. IVEY, a citizen of the United States, residing at New London, in the county of Stanley and State of 5 North Carolina, have invented certain new and useful Improvements in Pinless Clothes-Lines, of which the following is a specification.

This invention has relation to improvements in clothes-lines wherein clothes-pins are dispensed with and the line itself providing the holding device for the clothes hung or suspended therefrom, all as will be hereinafter more fully explained, and particularly pointed out in the appended claim.

The annexed drawings, to which reference is made, fully illustrate my invention, in which—

Figure 1 represents a side view of my improved line. Fig. 2 is a top or plan view of the same, and Fig. 3 is a detail view showing one end of one of the sections.

Referring by letter to the accompanying drawings, A designates the clothes-line, which is formed of sections *a a*, linked to one another. These sections have an eye *b* at each end, that engage each other and form a link connection. After this eye is formed the wire is twisted at *c* around the body portion and bent upward at *d* into a loop, which provides elasticity or spring for the spring-arm *e*, as well as a receiver for any of the clothing that may be forced inward toward the twisted portion *c*, thus taking up the slack of the clothing upon the line and depositing the surplus fabric within the space provided by the loop *d*. This spring-arm is bent horizontally at *f* and contacts with the horizontal body portion, and the end *g* of said spring-arm inclines upwardly and outwardly, providing a throat for the ready insertion of the article to be hung upon the line, and the extreme end

of said spring-arm is bent backward, as at *h*. As the ends of the sections of the line—*i. e.*, the twisted portions, eyes, and spring-arms—are duplicates of one another, I deem it necessary to describe but one, which is above set forth. 45

It will be seen that the sections of the line are permanently linked together and cannot be separated, and when the article of clothing is placed upon the line the operator forces the edge thereof into the throat of the spring-arm, which latter firmly holds the garment to the line-wire by the spring-pressure of the loop *d*, and in releasing the article therefrom 50 the same is simply drawn from engagement with the spring-arm and out of the throat thereof without the operator handling or manipulating the spring-arm, and my device can be used in hanging curtains, canopies, or mosquito-netting for beds as well as for clothing and is a device simple in construction, durable, and cheap to manufacture. 55

Having thus described my invention, what I claim, and desire to secure by Letters Patent, is— 60

The herein-described clothes-line comprising link-sections, each section provided with the spring-arm constructed with the throat-opening, a straight horizontal portion, and 65 upward and inwardly inclined portions forming a loop, said loop adapted to receive the surplus or slack of the clothing passed beneath the spring-arm, substantially as described.

In testimony whereof I have signed my name 70 to this specification in presence of two witnesses.

ROBERT W. IVEY.
